UNITED STATES PATENT OFFICE.

HUSTON H. MARRS AND HUSTON J. MARRS, OF DENVER, COLORADO.

DESIGN FOR A NAPKIN-DISPENSER.

4C,911.

Specification for Design.

Patented Feb. 2, 1915.

Application filed October 26, 1914. Serial No. 868,771. Term of patent 3½ years.

To all whom it may concern:

Be it known that we, HUSTON H. MARRS and HUSTON J. MARRS, citizens of the United States, residing in the city and county of Denver and State of Colorado, have invented a new, original, and ornamental Design for Napkin-Dispensers, of which the following is a specification, reference being had to the accompanying drawing, forming a part hereof.

The figure is a plan view of a napkin dispenser, showing our new design.

We claim:

The ornamental design for a napkin dispenser, as shown.

In testimony whereof, we affix our signatures in the presence of two witnesses.

HUSTON H. MARRS.
HUSTON J. MARRS.

Witnesses:

CHESTER P. DENNHARDT,
JNO. G. POWELL.
